LOUVER-TYPE RADIATOR GRILLE

Lee B. Green, Lakewood, Ohio, assignor to The
Globe Machine & Stamping Company, Cleve-
land, Ohio, a corporation of Ohio

Application December 14, 1932
Serial No. 647,230

22 Claims. (Cl. 293—54)

My invention relates to louver-type grilles, namely grilles or guards suitable for use at the frontal opening of the shell of an automobile radiator (or at windows), in which the guard members spanning the opening are composed of louver bars, and more particularly to grilles of this class in which at least the main portion of each louver bar is of a channel section.

Generally speaking, the objects of my invention are those of providing a grille of this type in which louver bars formed of light sheet metal can readily be attached at their ends to cross-bars and also to one or more stiffening bars extending between the cross-bars, in which frontal ornamenting beads can readily be snapped on the louver bars proper after the latter have thus been cross-connected, in which the louver bars will present no free rear edges to cause whistling, and in which the just recited advantages can be obtained in grilles affording widely varying frontal appearances.

In the louver-type grilles as heretofore employed in front of automobile radiators, it has already become customary to use sheet metal louver blades of rearwardly open channel section in place of the previously customary solid metal bars, thereby reducing the weight and cost of the grilles. However, this substitution of hollow sheet metal louver blades for solid grille bars has still left the following shortcomings, particularly in modern automobile practice where both a V-front appearance and a display of plated frontal grille parts is demanded even by purchasers of modest price cars:

1. With air moving at considerable velocity between such louver bars—as for example, when the car faces a wind or is driven at high speed—the air flowing past the rear web edges of a rearwardly open channel-sectioned blade causes an objectionable whistling. My present invention avoids this by providing effectively tubular louver bars each of which can be cheaply constructed of two sheet metal parts, each of which bars will present rounded and closed rear ends when the two parts are assembled.

2. With such grilles, the louver bars or blades cannot be plated with a durable coating of chromium or the like after the grille is assembled, because the grille then must be suspended in the plating bath with the fronts of the channel-sectioned blades facing the anode, so that the coating thins out toward the rear edges of the blades. On the other hand, a separate plating of each blade prior to the assembling of the grille adds to the cost of the plating and also allows portions

of the plating to be damaged during the assembling operations. My present invention avoids this by providing two-part louver bars, the main portion being of a forwardly open channel section which can be cheaply spray-painted after these main portions are attached to the end bars of the grille, and the auxiliary portion of each bar being a slotted tube which can cheaply be plated before attaching it to the main portion.

3. In my copending application #595,298, filed February 26, 1932 on a Louver type grille for automobile radiators, of which my present application is in part a division, I have disclosed and claimed various forms of two-part louver bars, designed so that the frontal ornamenting part of the bar can be slid longitudinally upon the main part of the bar, the two bar parts being thereafter clamped to each other by auxiliary means. In practice, such a bar assembly usually requires at least one end portion of the main bar part to be offset rearwardly so as to permit such a slidable assembly, thereby increasing the manufacturing cost.

Moreover, such a longitudinal sliding of one louver bar part on the other bar part is not feasible for a bar curved in side elevation; and even with straight-front bars, the ornamenting frontal part is apt to scrape parts of the coating off the main bar part if the latter has previously been coated.

My present invention overcomes these objections by providing a two-part louver bar construction in which the auxiliary part is snapped upon the front of the main bar part by a merely rearward movement, in which the main bar part can be of a uniform sectional shape throughout its entire length, and in which the two bar parts can readily be assembled even when the frontal edges of the bar are somewhat curved in side elevation.

4. Where the configuration of the radiator shell requires the louver bar to be of varying lengths, the requirement of a special forming of end portions of such bars, as for example the bar end types shown in my said copending application, considerably increases the cost of the assembling so as to eliminate an improper positioning of one or more of the bars. My present invention avoids this by providing end bars constructed so that the ends of the main louver bar parts will socket in these end bars in their proper relative positions, thereby also reducing the strains on interwelded portions.

5. The welding of intermediate cross-bars to the louver bars, as heretofore customary, also

adds considerably to the manufacturing cost. This I avoid by providing a construction whereby integral portions of the cross-bar and the louver bars will be interlocked by a simple assembling operation without requiring any welding or any auxiliary fastening elements, and whereby this interlocking will cooperate with the stiffening effect of the frontal bead parts of the louver bars to permit the use of lighter metal for the louver bars than has heretofore been required. Furthermore, I provide an interlocking cross-bar of this construction which can readily be modified by the forming of simple bends so as to cooperate in holding the louver bars parallel to each other when the grille is to have a V-front or other non-planular frontal appearance.

6. A further difficulty met in connection with automobile radiator grilles is that of firmly supporting louver bars which must be constructed of separate and aligned bar sections because these bars (if continuous) would extend across the opening provided in the radiator shell for the insertion of an emergency hand crank. The heretofore customary use of auxiliary plates for this supporting adds undesirably to the cost of the grille, which my invention avoids by providing a bowed connecting member between the two spaced parts of such a grille bar, and by having an adjacent continuous grille bar brace each such bowed connecting member, and by slightly deforming the adjacent ends of the connected bar parts to permit of a cheap and expeditious assembling.

Illustrative of my invention,

Fig. 1 is a rear elevation of horizontally central portions of an automobile radiator grille embodying my invention, also showing the corresponding portions of a radiator shell front having a central upright strip portion partially widened to afford an opening for a hand crank.

Fig. 2 is a frontal perspective view of an upper portion of the same grille.

Fig. 3 is a vertical section taken along the line 3—3 of Fig. 1, showing the anchoring of the upper end of one of the louver blades to the upper cross-bar of the grille.

Fig. 3A is an end view of a louver blade and of an ornamenting tube for the same, showing these two louver bar constituents before the tube has been snapped upon the blade.

Fig. 4 is a plan view of a portion of the grille, with dotted lines showing the downwardly extending flange on the upper cross-arm and the frontal blade-ornamenting tube.

Fig. 4A is a fragmentary plan view of a blade-connecting cross-member, showing a blade-receiving perforation in this member.

Fig. 5 is a section similar to Fig. 3, showing the assembly in a grille in which the louver blades slope forwardly downward.

Figs. 6, 7, 8 and 9 are plan views of upright ornamented louver blades with varying shapes of the split ornamenting tubes and the adjacent portions of the blades.

Fig. 10 is a section along the line 10—10 of Fig. 1.

Fig. 11 is a section along the line 11—11 of Fig. 1.

Fig. 12 is an enlarged section on the line 12—12 of Fig. 1.

Fig. 13 is a fragmentary frontal perspective view of the tabbed stiffening bar shown in Figs. 1 and 12 as initially formed.

Fig. 14 is an end view of this bar as initially formed.

Fig. 15 is a section allied to Fig. 10, showing two positions of the stiffening bar, during its attachment, both prior to the flattening of this bar and the clinching of its tabs to the louver blade.

Fig. 16 is an enlarged and fragmentary rear elevation of a portion of one of the louver blades.

Fig. 17 is a section taken along the line 17—17 of Fig. 16.

Figs. 18, 19 and 20 are sections respectively similar to Figs. 12, 14 and 15, showing the use of a stiffening bar in which the anchoring tabs initially extend in the same plane with the webs of this bar.

Fig. 21 is a fragmentary plan view, allied to Fig. 11, showing the stiffening bar as formed for 90 a V-front effect in the grille.

Fig. 22 is a partially sectioned side view of a louver bar and the top cross-member of the grille to which it is attached, showing the cross-member as including a web extending at right angles to 95 the forward and rear edges of the blade, and a frontal flange.

Fig. 23 is a fragmentary side elevation of the blade only of a U-sectioned louver blade shaped similar to those of Figs. 7 and 21, but with its 100 front and rear edges curved.

Fig. 24 is a fragmentary perspective view showing a slotted ornamenting tube snapped over the tube-fitting closed edge of a U-sectioned louver blade.

Fig. 25 is a transverse section showing a two-part assembly allied to Fig. 24 but with tube-engaging latch tabs on the louver blade.

Fig. 26 is a fragmentary perspective view of the tabbed blade of Fig. 25.

In the grille of Fig. 1, the guard portions, which effectively extend across the air-admitting opening O of the radiator shell front are upright and parallel louver bars, each consisting of rearwardly closed and generally U-sectioned blade 1 115 having the portions 1A adjacent to the forward edges of its two webs bowed apart, and a longitudinally slotted tube 2 snapped over these bowed forward web portions so as to close the frontal opening between the two webs of the blade. With 120 the blade initially formed (as in Fig. 3A) so that its bowed-apart portions are sprung by the resiliency of the metal to a greater total spread than the width W of the slit in the tube 2, and with the spread of the free edges of the two webs less than 125 the said slit width, the tube can readily be snapped over the oppositely directed ridges presented by the forward portions of the blade; by a forcible approaching movement along the medial plane P of the blade. During this attaching, the 130 bowed-apart web portions of the blade will approach each other sufficiently to pass through the slit in the tube, after which the resiliency of the blade will spread these web portions again so as to interlock them securely with the tube.

Each louver blade is fastened at its upper end to the upper cross-member or end member 3 of the grille, and to secure an expeditious and firm anchoring I preferably form this end member with suitably spaced perforations 4 (Fig. 4A) 140 each corresponding to the general contour of the blade when the frontal-tube is snapped on it. To permit the use of relatively thin metal for such an end bar, I desirably also deform portions of the bar adjacent to each of these 145 perforations 4 so as to constitute a flange 5 extending along the outer face of each web and preferably also contiguous to the back of the web. The companion lower end member would also have similarly located perforations and forma-

tions, as should readily be understood without picturing it.

After the blades have all been slid through (or at least into) the corresponding perforations in both end members, I fasten the blades to each end member by welds B or a corresponding brazing. This may be done even if each blade end only extends to the outward face of the adjacent member, as in Fig. 4, but I preferably make the blades sufficiently long (as shown in Figs. 1 to 3) to project somewhat beyond each end member, so as to expedite the welding or brazing. By thus having each blade extend into or through a correspondingly shaped perforation in each end member, I guard against an accidental improper positioning of one or more blades, such as would occur in ordinary manufacturing if the blade ends merely abutted against the end members; and I also afford much more convenient access for the welding, particularly when the blades are rather closely spaced. And by also forming each end member so as to present flange portions against which at least the side webs of the blades bear I greatly enhance the rigidity of the assembly, thereby permitting quite thin and light end members to be employed in place of the thick bars heretofore commonly used for this purpose.

Where the grille is to be disposed behind a radiator shell front which has a frontal part affording an auxiliary opening A for admitting a hand crank, some of the louver bars may need to be positioned where they would extend partly across this opening, so that each of these louver bars must be made of two aligned sections spaced to afford ample clearance for the crank. To permit of this while still securing the desired rigidity for the aligned sections of each such bar, I connect the free ends of each such two louver blade sections 1B and 1C by a connecting strap which is bowed laterally around the opening A as in Fig. 1. For this purpose, I preferably first flatten the blade webs of each end portion of the two blade sections against each other, as shown at 1D in Fig. 1, and then weld the end portions 6A of a flat connecting strap respectively to the flattened end portions of the two blade sections.

Since an otherwise free bowed strap might flex undesirably, I also form the medial portion 6B of this strap so that it bears flatwise against the next adjacent blade, as shown in Fig. 1, and preferably flatten the portion 1D of that blade to which the strap is then also welded. Each such connection between a continuous blade and an adjacent two-section blade can readily be made before the blades are attached to the end members of the grille, thereby bracing the two-section blade to a continuous one.

For a further stiffening of the grille, I also employ at least one stiffening bar S extending across the backs of all of the blades, which bar fits into a notched rear end portion of each blade and has integral tabs anchoring it to the blade. For this purpose, I form a transverse groove in the back of each blade, as shown in Figs. 16 and 17, and employ a stiffening bar which is initially of an angle section, as shown in Fig. 13, with the joint width of its webs corresponding to the width of the said groove.

Projecting from the free edges of the webs of this bar are pairs of tabs T, which pairs of tabs are spaced from each other to match the spacing of the grille blades, each tab desirably having its

main portion extending parallel to the web to which it is attached and connected to the adjacent web edge by a short tab portion T¹ to offset the main tab portion from that web in a direction inward of the angle between the two webs.

With the tabs of suitable length, the stiffening bar can initially have all the tabs at one edge of the bar slipped into the interior of the several blades, as shown in full lines in Fig. 15, after which the bar is swung to the position shown in dotted lines, so as to have both edges engage the groove bottom 10B on both webs of the blade. When the bar is then flattened by a press-plunger 11 (as also shown in dotted lines in Fig. 15), the two webs of the bar are brought into alignment with each other and pressed flatwise against the groove bottom 10B, and during this deforming of the bar the main portions T¹ of the tabs are swung against the inner faces of the backs of the blades. Thus attached, each blade is latched against transverse movement (or flexing toward either side) by the tabs, and the engagement of the free edges of the stiffening bar with the groove ends 10A also prevents any rocking of that bar in its own general plane, so that I produce a rigid assembly even when using a stiffening bar of thin sheet metal bar, and without requiring any welding or brazing.

Since the attached stiffening bar seats on both of the spaced groove bottoms 10B (Fig. 16) of each blade, this simple attaching also anchors the blades against rocking about the bar so as to swing their medial planes P (Fig. 11) out of parallel relations, thereby preventing any mid-height twisting of the blades even when these are formed of quite thin metal. However, this does not limit my construction to flat-fronted grilles, since other frontal effects can readily be provided by providing suitable offsets 13 in the stiffening bar, as shown in Fig. 21 for a part of a V-front grille.

In practice, the blades of my grille can speedily be cut to their proper lengths from long metal strips formed to the selected uniform section, and then attached to the end members (as heretofore described) without requiring any deforming of the end portions of the blade ends, so that the entire manufacture of my rigid grille is both inexpensive and expeditious. Moreover, many changes may be made without departing either from the spirit of my invention or from the appended claims.

For example, instead of having the latching portions of the tabs T on the stiffening bar offset from the adjacent web portions of that bar, the tabs may be entirely in the same plane with the remainder of the bar, it being merely necessary to provide a suitable depth of the groove 10 in each blade. Thus, Fig. 20 shows the initial section of a thus modified bar, Fig. 19 a step in the attaching, and Fig. 18 the position of that bar when attached to a grille blade.

So also, the cross-sectioned shape of the frontal portions of the grille blades and of the attached longitudinally slotted tube may be varied considerably, as shown for example in Figs. 6 to 9 inclusive. With the interior section of this tube 2 an incomplete circle, the bowed-apart frontal web portions of each blade may be formed (as in Figs. 2, 6 and 10) so that blade web portions will engage the bore of the tube both forwardly and rearwardly of a diametric plane 14 (Fig. 6) through the tube at right angles to the medial plane P of the blade to which the tube is at-

tached, thereby insuring a rigid attaching even when the tube is formed of quite thin metal.

Moreover, in thus constructing two-part louver bars, the blades need not necessarily be formed so that their forward web ends are sprung apart before the tube part is attached, or so that these web portions again spring apart after the attaching of the tube. For example, Fig. 9 shows a blade which might be rigid and non-resilient if the attached tube is so thin and resilient as to allow the tube to spread open sufficiently for snapping upon the blade.

With all of the illustrated two-part louver bars the frontal tube portions can readily be snapped to the blades after these blades have been fastened both to the end bars and to one or more intermediate stiffening bars, and after the resulting assembly has been spray-painted or otherwise coated. This allows the slotted tubes to be differently finished—as for example by chrome-plating them—to enhance the appearance of the grille. With the blades sufficiently resilient, such tubes can even be snapped upon the blades when the latter have a somewhat curved frontal contour in side elevation (or even an ogee curvature as shown to an exaggerated extent in Fig. 23), which would not be possible if the tube had to be slid lengthwise over the frontal blade portions.

Since the slotted tubes can readily be snapped upon the blades after the latter have been fastened to the end bars of the grille, my two-part louver-bar construction also permits the use of end members of an angle section. Thus Fig. 22 shows the upper end bar 3 of the grille as having a supplemental web 3A depending from the forward edge of the web to which the blades are fastened.

It will likewise be obvious that with a slotted tube part straddling the free web edges of a generally U-sectioned blade (after the manner of Figs. 6 to 9) the resulting louver bar is closed at both edges, and could be used also with the back of this blade at the front and with the slotted tube facing rearwardly of the grille.

Indeed, my slotted auxiliary tube can also be employed for ornamenting the forwardly directed U-back edge of a louver blade, as shown for example in Figs. 24 to 26. In Fig. 24, the louver blade 16 has a cross-section resembling that of an uncompressed spring cotter, the closed edge portions 16A being spread out after the manner of an eye and fitting the bore of the slotted tube 2.

In Figs. 25 and 26, the blade 17 is of a simple U-section except for its extreme free edge portions 17B (which are here shown as bent toward each other to prevent a possible whistling effect) and each web of the blade has rearwardly directed tabs 17A or fingers projecting outwardly away from that web for engaging the bore of the slotted tube 2 as shown in Fig. 25, these latch tabs being spaced longitudinally of the blade.

However, while the heretofore described features of grille construction readily cooperate in meeting all of the recited objects of my invention, I do not wish to be limited to the conjoint use of these numerous features. Nor do I wish to be limited to the purposes for which a grille or guard embodying any of the here disclosed novel structural features is used.

I claim as my invention:

1. A louver for a grille or the like comprising a generally U-sectioned louver blade presenting a closed back, two webs extending forwardly from

the said back, portions of the said webs near the free edges of the latter being bent away from each other, and a longitudinally slotted tube snapped over the said bent away portions of the blade to latch the tube to the blade and to close the opening between the free edges of the said webs.

2. A louver as per claim 1, in which the bent-away portions of the said webs have a wider spread, before the snapping of the slotted tube on the blade, than the width of the said slit, and in which one of the members is resilient to permit the recited assembling and to hold the two members interlocked thereafter.

3. A louver bar for a grille or the like comprising a generally U-sectioned main part presenting an imperforate back and two spaced webs extending forwardly from the said back, and a longitudinally slotted tube extending in front of both webs and straddling the forward edge portions of both webs of the said main part, the said forward portions of the two webs being of greater joint spread than the width of the slit in the tube.

4. A louver bar as per claim 3, in which each of the said forward web portions engages the bore of the tube both forwardly and rearwardly of a longitudinal plane diametric of the tube and at right angles to the medial plane between the two webs.

5. A louver bar for a grille or the like comprising a generally U-sectioned and resilient main part presenting an imperforate back and two spaced webs extending forwardly from the said back, and a longitudinally slotted tube extending in front of both webs and straddling both of the said webs, the forward portions of the two webs having hook formations formed for hookingly engaging parts of the bore of the tube rearwardly of a longitudinal plane diametric of the tube and at right angles to the medial plane between the two webs.

6. A louver bar for a grille or the like comprising a generally U-sectioned and resilient main part presenting an imperforate back and two spaced webs extending forwardly from the said back, and a longitudinally slotted tube extending in front of both webs and effectively closing the frontal opening between the two webs, the forward portions of the two webs having oppositely directed formations engaging the bore of the tube, the lateral spread of the formations on the two webs being greater than the width of the slit in the tube, the resiliency of the said main part permitting its webs to flex toward each other to reduce the said spread to the width of the said slit to allow the tube to be snapped upon the main part by a relative movement of the tube with respect to the said main part in a medial longitudinal plane of both thereof.

7. A louver blade as per claim 6, in which the said formations of the two webs of the main bar part extend continuously along substantially the entire length of that part.

8. A grille comprising substantially parallel louver blades each of a U-shaped section, and spaced blade-connecting members extending transversely of the longitudinal axes and of the U-shanks of the said blades; each such member having perforations each conforming to the exterior contour of a blade and into which perforations the blades respectively extend, and the end member having flanges adjacent to each perforation and respectively engaging the opposite sides of a blade and extending longitudinally of the blade.

9. A grille comprising substantially parallel and upright louver blades each of a U-shaped section, and an end member extending transversely of the said blades adjacent to one end of all 5 blades; the end member having perforations each conforming to the exterior contour of a blade and into which perforations the blades respectively extend, and also having adjacent to each blade a flange extending longitudinally of the 10 blade and engaging the U-back of that blade.
10. A grille comprising spaced and substantially parallel louver blades each having its rearward portion of a U-section presenting its U-bottom rearwardly, the said blades having counterpart 15 and alined transverse grooves extending across their said U-bottoms to afford rearward openings; and a blade-connecting member extending transversely of the said blades and through the said alined grooves and bearing against the bottoms of the grooves, the said member having pairs of oppositely directed edge tabs, the tabs of each pair extending longitudinally of one of the 20 blades in front of and in engagement with the forward face of the U-bottom of that blade so as to clinch the said member to that blade.
11. A grille as per claim 10, in which each of the said grooves has parallel end walls respectively engaged by the upper and lower edges of the blade-connecting member.
- 30 12. A stiffening member for rigidly connecting substantially parallel U-sectioned louver blades, which blades have alined and counterpart transverse grooves extending across their U-backs; comprising a sheet metal strip of angle section presenting two diverging webs and having the joint width of the said webs substantially equal to the uniform width of the said grooves, the 35 said strip having tabs projecting from the free edges of its webs, the said tabs being arranged in pairs spaced similarly to the spacing between the 40 medial longitudinal planes of the louver blades.
13. A louver-blade stiffening member as per claim 12, in which each tab has its free end portion offset from the portion of the web carrying that tab, the offsetting being toward the interior 45 of the angle at which the said webs diverge.
14. A louver-blade stiffening member as per claim 12, in which each tab has its free end portion offset from the portion of the web carrying 50 that tab, the offsetting being toward the interior of the angle at which the said webs diverge and the offset portion of each tab extending substantially parallel to the web from which the tab projects.
- 55 15. A louver bar for a grille or the like, comprising a main bar part and an auxiliary bar part straddling one longitudinal edge of the main bar part and gripping opposite side faces of the main bar part, the main bar part having on its 60 opposite sides outwardly directed formations interlocking with the auxiliary part to latch the latter to the main bar part.
16. A louver bar as per claim 15, in which the auxiliary bar part is a longitudinally slotted tube, 65 and in which at least one of the said parts is sufficiently resilient to permit the slit-bordering parts of the tube to ride and snap over the said formations on the main bar part during the attaching of the auxiliary bar part.
- 70 17. A louver bar for a grille or the like comprising a generally U-sectioned main part presenting two side webs, and an auxiliary part consisting of a slotted tube straddling the free edge portions of the said webs, at least one of 75
- the said parts being formed of metal of sufficient resiliency so as to latch the parts to one another.
18. As a constituent for a louver-type grille, a grille blade presenting one of its longitudinal edges forwardly of the grille, and a longitudinally slotted tube straddling the forward edge of the said blade, portions of the blade adjacent to the forward edge thereof being of greater normal spread than the normal width of the said slit; the said portions engaging the bore of the tube when the tube is attached to the blade, so as to anchor the tube to the blade.
19. In combination, a frontally apertured automobile radiator shell having a frontal opening and having a front portion extending radially inward of the said frontal opening, the said front portion being provided with an auxiliary aperture; and a separately constructed grille comprising two sets of substantially parallel louver bars extending across the said frontal opening at opposite sides of the said apertured front portion, and two louver bars disposed between the said two sets of bars; each of the last named two bars comprising a lower portion and an upper bar section alined therewith, and a connecting member having its end parts fastened respectively to the adjacent end parts of the said two bar sections; the connecting members of the last named two bars being bowed away from each other and concealed respectively by parts of the said front portion which are at opposite sides of a plane medial of the said aperture and parallel to the said upper and lower portions of the said two bars.
20. A radiator shell and grille combination as per claim 19, in which the connecting member of each of the last named two louver bars is fastened to the nearest louver bar of the set of the first named bars which is at the same side of the aperture with that connecting member.
21. A radiator shell and grille combination as per claim 19, in which the connecting member of each of the last named two louver bars is a flat strip bowed transversely of its flat faces and is secured flatwise to a side face of the nearest louver bar of the set of the first named bars which is at the same side of the aperture with that connecting member.
22. For use behind an automobile radiator shell front which front has an air-admitting opening and has a front portion affording a crank-admitting aperture at higher elevation than the lower edge of the said opening, a grille comprising two sets of continuous and substantially upright louver bars extending across the said opening respectively at opposite sides of the said aperture, and two louver bars disposed between the aforesaid sets of louver bars; each of the last named two louver bars including an upper portion and a lower portion alined with each other and substantially parallel to the louver bars of the said two sets, and also including a bowed portion connecting the said upper and lower portions; the bowed portions of the said two louver bars being bowed away from each other and respectively concealed by the parts of the said front portion at opposite sides of the said aperture, and each of the said two louver bars having its bowed portion fastened to the laterally innermost louver bar of the set of bars which is at the same side of the said aperture with that bowed portion.

LEE B. GREEN.
